TIMKEN ROLLER BEARING COMPANY, OF CANTON, OHIO, A CORPORATION OF
OHIO.

MACHINE FOR CLOSING CAGES OF ROLLER-BEARINGS.

1,375,384.

Specification of Letters Patent. Patented Apr. 19, 1921.

Application filed March 19, 1920. Serial No. 367,050.

To all whom it may concern:

Be it known that we, ERNEST G. STRONG and EARL C. ROHN, citizens of the United States, and residents of the city of Canton, 5 in the county of Stark and State of Ohio, have invented a new and useful Improvement in Machines for Closing Cages of Roller-Bearings, of which the following is a specification.

Our invention relates to machines for closing in the cages of roller bearings; and it has for its principal objects to devise a machine that will automatically press the cage stays into proper relation to the rollers and 15 to each other; to devise means for accomplishing this result without exposing the hands of the operator to danger and which will operate rapidly and economically. The invention consists in the parts and combinations of parts hereinafter described and claimed.

In the accompanying drawing wherein like numerals refer to like parts wherever they occur,

Figure 1 is a plan view of the closing-in die embodying our invention, parts being broken away to more clearly illustrate the invention;

Fig. 2 is a fragmentary side view of a power-press showing the closing-in die in position on the bed of the press;

Fig. 3 is a vertical section taken through the closing-in die on the line 3—3 in Fig. 1;

Fig. 4 is a fragmentary vertical section 35 taken through the work receiving opening of the machine, the cage, inner bearing member and rollers shown in position in the work receiving opening and the finger plate being shown in a position prior to their engagement with the bridges of the cage.

Fig. 5 is a diagrammatic view illustrating the manner in which the finger plates engage the bridges of the cage;

Fig. 6 is a vertical section through the slot 45 in which the plunger works, the section being taken on the line 6—6 of Fig. 1 and the plunger being shown ready to engage the beveled surface of the cam ring block; and

Fig. 7 is a vertical detail section taken 50 through the plunger and plunger holder.

Our machine is primarily intended for operation on roller bearings of the kind illustrated in Alden Patent No. 921,656, dated May 18, 1909. A cage of this type is shown 55 in Figs. 4 and 5 of the accompanying drawings and comprises annular end members A

connected by longitudinally disposed bridges B, which are provided with flaps C or the like to form pockets for the rollers D; and such cages are usually made of sheet metal 60 cut and pressed into shape. The rollers are disposed in the pockets of the cage with the inner bearing member E in position inside of the cage. In the process of making the cage or in the subsequent handling thereof, 65 the bridges are liable to be more or less bowed endwise; and it is necessary to "close in" all of the bridges, that is, to bring them into proper relation to the rollers throughout their length. According to our invention, the closing in operation is effected upon 70 all of the bridges simultaneously by a series of fingers, which are actuated by a cam, and are equal to the bridges in number and arranged to operate against said bridges, with 75 respect to the axis of the cage.

Referring to Fig. 1 of the drawings, our device comprises a die block 1, adapted to be mounted on the bed 2 of the well-known type of power-press, and a tapered plunger 80 3 whose upper end portion is held in the vertical reciprocating slide bar 4 of the press in a usual manner. This slide bar works in vertical slide ways formed in the frame of the press and is mounted on the lower end of 85 the ram or pitman 5 thereof. This pitman receives its motion from an eccentric on a shaft which, upon depressing a foot-treadle, is rotated one complete revolution and causes the ram to descend and ascend. This mechanism for lowering and raising the slide bar 90 is well-known, and, therefore, it is not shown in the accompanying drawings.

The die block 1, which can be secured 95 to the bed 2 of the press in any desired manner, comprises an outer member 6, an inner member 7 and a top cover plate 8. The outer member is preferably made in the form of a cylindrical shell or casing whose inner wall is offset inwardly at the 100 base thereof to form an inwardly projecting annular shoulder or horizontal ledge portion 9. This shoulder forms an opening of reduced diameter in the base of the casing which is concentric with the opening 105 in the upper portion thereof. The inner member 7 is located centrally within the casing and comprises a circular base flange 10, which fits within the reduced opening formed by the annular shoulder 9 of the 110 casing to close the same, and a concentric cylindrical portion 11 of reduced diameter,

which projects upwardly from the base flange and terminates flush with the upper surface of the die casing. The cylindrical portion 11 of the inner member is concentric with the cylindrical die casing and is spaced from the inner wall thereof, thus forming an annular recess 12 in the upper face of the die. The upwardly projecting cylindrical portion 11 of the inner member 5 is provided with a central bore whose lower portion 13 is cylindrical and whose upper portion 14 tapers outwardly from the cylindrical portion 13 of the bore to the top of the cylindrical portion 11 of the inner member. A tubular sleeve 12^a is fitted within the cylindrical portion 13 of the central bore of the inner member. The upper edge of this sleeve is beveled to form a seat for one of the annular end members A of the 10 roller cage. The tapered portion 14 of the central bore of the inner member is provided with a series of shallow concavities 15 of a curvature corresponding to the conical surfaces of the bearing rollers D. The 15 inner member is held in position in the outer die casing by means of a series of cap screws 16, which extend horizontally through the shoulder portion 9 of the die casing and are threaded into the circular base flange 10 of the inner member 7. The cover plate 8, which is of the same diameter as the die casing, fits over the top of the casing and closes the annular recess 12 formed in the die. The cover plate has a beveled central circular opening 17 which surrounds the upper end of the tapered portion 14 of the central bore in the inner member 7. The outer margin of the cover plate 8 is secured to the die casing 6 by means of 20 cap screws 18, which extend vertically through the cover plate 8 and are threaded into the wall of the die casing. The cover plate is also secured to the inner member 7 by means of a series of cap screws 19, 25 which extend vertically through the cover plate adjacent to the central opening 17 thereof, and are threaded into the upper end of the cylindrical portion 11 of the inner member.

30 A ring 20 is arranged for rotation within the annular recess 12, which is formed by the inner member 7 and outer member 6 of the die, and is supported on the annular shoulder 9 of the outer die casing. A block 35 21 is dovetailed into the outer wall of the ring 20 and projects horizontally therefrom. This block is further secured to the ring by means of cap screws 22 which extend horizontally through the block and 40 are threaded into the ring. The annular recess 12, adjacent to the block 21, is extended outwardly through the wall of the die casing into an extension 23 of the die casing in the form of a pocket 24. This 45 pocket is not covered by the cover plate 8 and is of a width sufficient to accommodate a movement of the ring block 21. The ring 20 has a series of equally spaced vertically disposed grooves formed in its inner wall in which are located a series of cam blocks 70 25. These blocks extend from top to bottom of the ring and are secured in their slots by means of cap-screws 26, which extend horizontally through the ring and are threaded into the blocks 25. The inner 75 faces of the blocks are beveled as at 26^a, the angle being such that the inner vertical edge of each block, facing the direction in which the ring rotates, is further away from the cylindrical portion 11 of the inner member than the opposite vertical edge of the block. The beveled faces 26^a of the blocks 25 are adapted to engage the outer edges of a series of vertically disposed finger plates 27.

80 These plates 27 are arranged for horizontal sliding movement in a series of vertically disposed radially spaced slots 28 formed in the cylindrical portion 11 of the inner member 7. These slots extend from 90 the outer wall of the cylindrical portion 11 of the inner member to the wall of the tapered portion 14 of the central bore therein. The inner edges of the finger plates 27 are beveled as at 29 and project a suitable distance beyond the tapering portion 14 of the central bore of the inner member 7 in their normal (outermost) positions. The finger plates are held in their outermost 95 positions by means of coil springs 30. These 100 springs are mounted in a series of radially spaced horizontal pockets 31 which extend inwardly from the outer surface of the cylindrical portion 11 of the inner member of the die. The pockets 31 are located 105 close to the finger plates 27 and their walls, adjacent to the plates, are slotted as at 32 to permit pins 33, which project from the finger plates, to enter the pockets. These pins 33 project from one side of the finger plates 110 27 and extend through the slots 32 therefor across the outer ends of the coil springs 30.

115 The ring block 21 is held against a vertical stop plate 34 in the pocket 24 of the extensions 23 of the die casing 6 by means of coil springs 35. These springs are located in horizontal slots 36 cut in the side wall of the outer case on opposite sides thereof. One end of each spring is attached 120 to a vertical pin 37 threaded into the bottom of the slot 36 therefor and its opposite end is attached to the outer end of a pin 38 which is threaded into the cam ring 20. These slots are of sufficient length to enable the pins 38 125 to move with the cam ring and stretch the springs 35 when the ring is rotated.

130 Extending through the extension 23 of the die casing 6 from top to bottom thereof, is a vertical slot 39. This slot is provided

- with spacing plates 40 and a guide plate 41. The face of the ring block 21, adjacent to the guide plate 41, is provided with a projecting lug portion 42 whose upper surface 43 is beveled from top to bottom. The angle of the beveled surface of the ring block corresponds to the angle of a beveled surface 45 on the plunger 3, which is held in the slide bar 4 of the power-press.
- 10 This plunger is located directly above the beveled surface 43 of the ring block 21 and has a cylindrical shank portion 46 slidably mounted in a bore of a cylindrical holder 47. This plunger holder is clamped in a hole in the slide bar 4 of the press in any desired manner. The plunger 3 has a reduced cylindrical portion 48 which extends upwardly through a reduced bore therefor in the punch holder 47. The upper end of the reduced portion 48 of the shank portion of the plunger projects above the upper end of the punch holder and is threaded to receive an adjusting nut 49 and a lock nut 50. The plunger 3 and the plunger holder 47 are 15 both provided with annular flanges 51. A heavy coil spring 52 is arranged between the respective flanges 51 of the punch and punch holder and thus holds these two members apart. With this arrangement the 20 stroke of the plunger may be varied by tightening or loosening the adjusting nut 49. The action of tightening this nut causes the plunger 3 to be drawn up into the plunger holder 47, thus increasing the space between the lower end of the plunger and the 25 top of the die. When the nut is loosened, this action permits the spring to force the plunger downwardly and thus lessen the distance between the lower edge of the 30 plunger and the top of the die.
- The operation of the machine is as follows: The cage with the rollers in the pockets thereof and with the inner bearing E in position therein is dropped into the tapered portion 14 of the central bore of the inner member of the die, with its bottom (smaller) annular end flange resting on the upper end of the tubular sleeve 12^a located in the cylindrical portion 13 of the central 35 bore in the inner member 7. The upper edge of this sleeve is beveled to conform to the inclination of the annular flange of the cage which rests thereon. The outer surfaces of the rollers fit into the shallow 40 cavities 15 formed in the wall of the tapered bore 14 and the bridges of the cage are arranged opposite the beveled inner ends of the finger plates 27. Thereupon the power-press is actuated and causes the plunger 3 to 45 descend which action causes the beveled surface 45 thereof to engage the corresponding beveled surface 43 of the ring block 21. The wedging action resulting from the engagement of the two inclined faces of the plunger 3 and ring block 21 forces the cam ring 50 in the direction indicated by the arrow H in Fig. 1 and causes the cam ring to be partially rotated. This partial rotation of the cam ring 20 causes the beveled cam faces 26^a of the cam blocks 25 secured thereto to 55 engage the outer ends of the finger plates 27 and force the same inwardly. This inward movement of the finger plates causes their beveled inner edges to bear against all of the bridges B of the cage simultaneously 60 with sufficient force to straighten out the bridges and to bring them into proper relation to the rollers D of the bearing. This inward movement of the fingers 27 also tends to spread the flaps C, which form the 65 pockets for the rollers, and causes these flaps to embrace the rollers. With the construction illustrated in the drawings, the operation is effected quite rapidly and with great safety to the operator. The source of power 70 is a press of an ordinary type; but instead of the work being under the plunger, it is considerably offset therefrom; that is to say, the tapering bore in which the work fits is considerably removed from the press. Thus, 75 in feeding the machine, the operator's hands are quite free from danger.
- What we claim is:
1. In a machine for closing in conical roller bearing cages, a press having a plurality of radially disposed horizontal plungers, angularly spaced to conform to the spacing of the bridges of a cage and having their inner ends beveled to conform to the taper of such cage, cam means for simultaneously moving said plungers, and an operating member arranged to actuate said cam means. 80
2. In a machine for closing in roller bearing cages, a press having a horizontal bed plate, a die mounted on said bed plate and having an opening adapted to receive a conical cage, a plurality of radially disposed horizontal plungers surrounding said opening, a cam ring surrounding said plungers 85 for simultaneously moving the same inwardly, and a vertically operating member arranged to actuate said cam ring, said operating member being offset with respect to the central axis of said opening, whereby 90 the fingers of the operator may be kept out of the danger zone. 95
3. In combination with a press having a bed plate and a vertically movable plunger, of a die supported on said bed plate, said die having a circular opening adapted to receive roller bearing cages, work engaging means in said die disposed and movable radially of said opening and adapted to engage the bridges of cages in the receiving 100 opening thereof, means for actuating said work engaging means, said actuating means having a projecting portion offset with respect to the opening of said die and lying in the path of the movable plunger of said 105

- press so as to be actuated thereby and having cam surfaces adapted to engage the work engaging means to actuate the same when engaged by said press plunger, and 5 springs for automatically returning said work engaging means and said actuating means to normal position.
4. A press for closing in cages of roller bearings having a bed plate and a vertically 10 movable slide plate, a yieldable plunger on said slide plate, means for varying the length of said plunger, a die supported on said bed plate, said die having a circular opening adapted to receive the work, said 15 opening being offset with respect to said plunger, a series of plates disposed and movable radially with respect to said opening for engaging the work therein, and means for actuating said work engaging plates,
- 20 said actuating means having a portion extending into the path of said plunger so as to be engaged by said plunger to actuate said work engaging plates.
5. In combination with a press having a 25 bed plate and a vertically movable plunger, of a die supported on said bed plate, said die comprising a hollow casing having a central opening therein adapted to receive the work, a series of radially slidable fingers located 30 in said die and extending into said central opening, a ring located in said die and surrounding said fingers, said ring having cam faces adapted to engage said fingers for moving the same toward the axis of the work 35 receiving opening and being adapted to be engaged by said plunger, whereby said ring when engaged by said plunger will be partially rotated and cause the cam faces thereof to engage the fingers and force the same 40 inwardly toward the axis of the opening in said die, and means for returning said cam ring and said fingers to their normal positions.
6. A die comprising a casing having a 45 central opening adapted to receive the work, a series of radially spaced finger plates slidably mounted in said die casing and extending through the wall of the central opening therein, yieldable means for normally holding 50 said fingers in their outermost positions, a ring rotatably mounted within said casing, said ring surrounding said finger plates, series of cam blocks removably secured to the inner face of said ring and being adapted 55 to engage the outer ends of said finger plates, said ring having a projected portion provided with a beveled face, a stop for said ring, yieldable means for holding the projecting portion of said ring against said 60 stop and for holding the removable cam blocks thereon out of engagement with said finger plates, and a movably mounted plunger for actuating said ring, said plunger having a beveled portion adapted to engage 65 the beveled face of the projecting portion
- of said ring to cause the ring to be partially rotated, whereby the cam blocks thereon engage the finger plates and force the same inwardly toward the axis of the central opening in said die. 70
7. A die for closing in roller bearing cages of the kind which comprise spaced annular end members connected by annularly spaced bridges which form pockets for the rollers, said die comprising a casing 75 having a central opening adapted to receive the bearing cage with the rollers in the pockets thereof and an inner bearing member, series of radially spaced finger plates slidably mounted in said casing, the inner ends of said fingers extending through the wall of said central opening, a cam ring surrounding said fingers and having cam faces adapted to engage the outer ends of the same, and means offset from the work receiving opening for partially rotating said ring to cause the cam faces thereof to engage the fingers and force the same inwardly against the bridges of the cage to bend the same inwardly toward the axis 80 thereof. 85
8. A die for closing in roller bearing cages of the kind which comprise spaced annular end members connected by annularly spaced bridges provided with wing portions 90 which form pockets for the rollers, said die comprising a casing having a central opening adapted to receive the bearing cage with the rollers in the pockets thereof and an inner bearing member, series of radially spaced finger plates slidably mounted in said casing, the inner ends of said fingers extending through the wall of said central opening, a cam ring surrounding said fingers and having cam faces adapted to engage the outer ends of the same, means for normally holding the cam faces of said ring out of engagement with said fingers, means 95 offset from the work receiving opening for partially rotating said ring to cause the cam faces thereof to engage the fingers and force the same inwardly against the bridges of the cage to bend the same inwardly toward the axis thereof and to spread the wing portions of said cage apart, and means for automatically returning said cam ring and said fingers to their normal positions. 100
9. A plunger for a die press, said plunger comprising separate members sleeved one in the other, a spring for holding said members apart, one of said members extending through the other of said members and having adjustable means thereon for drawing said members together and for separating them, and means for locking said adjustable 105 means. 110
- Signed at Canton, Ohio, this 18th day of February, 1920.
